UNITED STATES PATENT OFFICE

HAROLD A. GREENWALD, OF DETROIT, MICHIGAN, ASSIGNOR TO THOMAS C. WHITE-HEAD, OF DETROIT, MICHIGAN

SEAL CONSTRUCTION

Application filed January 30, 1928. Serial No. 250,624.

This invention relates to pump constructions and has particular reference to the means employed for sealing the main shaft of the pump whereby the escape of fluid or the entrance of air along the main shaft is prevented.

The invention, while capable of many diversified uses, finds particular utility in connection with refrigerating apparatus where-
10 in it is essential to the efficient operation of the apparatus to provide some means for sealing the main shaft of rotary type pump.

While many forms of seals have heretofore been used for accomplishing the fore-
15 going purpose, it has been found, that owing to the particular disposition of these seals in the system that they were required to resist considerable pressure and accordingly had a tendency to leak.

20 It is therefore one of the primary objects of the present invention to provide a construction wherein the sealing means is disposed within a chamber arranged in communication with the return line of the sys-
25 tem so that the seal will be required to resist only the pressure of the refrigerant in the low pressure side of the system and as a consequence be less likely to leak.

Other objects and novel details of construction will be made more apparent as this description proceeds, especially when considered in connection with the accompanying drawing wherein,

Figure 1 is a fragmentary vertical sec-
35 tional view through a pump showing the particular arrangement of the seals; and

Figure 2 is a view similar to Figure 1 showing a modified form of construction.

In general the device comprises a pump
40 10 of any suitable design but preferably of the rotary type, the one illustrated having the intermeshing gears 11 and 12 keyed upon the stub shaft and main shaft 13 and 14 respectively. The main shaft 13 prefer-
45 ably projects through one wall 15 of the pump casing and is adapted to be connected to a suitable prime mover (not shown). Ex-
50 tending outwardly from the wall 15 of the casing is a tubular projection 16 surround-
55 ing a portion of the shaft 13 and normally

closed by a cap 16' sleeved upon the shaft and bolted or otherwise detachably secured to the outer end of the projection 16 forming therewith an annular chamber 17. As shown, the chamber 17 is provided at the 55 lower end thereof with an opening 18 for receiving one end of the conduit 19 connected to the usual expansion coils (not shown). Thus it will be noted that the conduit 19 functions as a return passage for 60 the refrigerant from the expansion coils to the pump and further that the chamber 17 constitutes an intake chamber for the refrigerant prior to its escape, through the 65 passage 20 formed in the wall 15, into the pump so that the chamber 17 is on the low side of the system and accordingly is subject only to the low pressure of this side.

Arranged within the chamber 17 and sur-
70 rounding the shaft 13 is a double seal construction indicated generally by the reference character 21. This seal construction may be of any desirable design, but preferably comprises a pair of seals, for instance, an inner seal 22 and an outer seal 75 23. The inner and outer seals are preferably of substantially the same design and comprise the nuts 24, headers 25, bellows 26 and coil springs 27. As shown, the nuts 24 threadedly engage the shaft adjacent to and 80 upon opposite sides of the enlarged portion 28 of the shaft and maintain gaskets 27 against the inner and outer shoulders 30 and 31 respectively formed by the enlarged portion 28. The headers 25 of both the outer 85 and inner seals frictionally engage the inner wall of the cap 16' and the outer wall of a plate 32 respectively. As shown the plate 32 is detachably secured within a recess formed in the end wall 15 of the pump cas-
90 ing substantially flush with the outer surface thereof. The springs 27 preferably surround the shaft 13 between the headers 25 and nuts 24 so as to yieldably maintain or urge the headers into engagement with the cap 16' and plate 32 as heretofore pointed out. The bellows 26 also surround the shaft 13 and together with the coil springs 27 are terminally secured to the nuts 24 and headers 25. Thus from the foregoing, it will be 100

noted that the parts 24, 25, 26 and 27 respectively of the double seals rotate as a unit with the shaft so that any fluid escaping from the inside of the pump casing along the shaft and into the chamber between the header 25 and outer wall of the plate 32 will be thrown by centrifugal force away from the seals so that the oil will not flow between the outer header 25 and cap 16'. 5

Moreover with the foregoing arrangement, it will also be noted that inasmuch as the inner seal will function to normally prevent any fluid escaping from the pump casing into the chamber 17, the outer seal will be required to resist only the escape of the refrigerant contained in the chamber 17 which is at its lowest pressure owing to the fact that the chamber 17 is in the low pressure or expansion side of the system. However, 15 in the event that fluid leaks past the inner seal, the outer seal will also operate to prevent the fluid from escaping along the shaft 13 to the exterior of the chamber 17. 20

Referring now to the modified form of the invention illustrated in Figure 2, it will be noted that the particular arrangement of the intake chamber in the system is substantially the same as in the first described form, the only material difference 30 between the two forms of the invention is that the two seals 33 and 34 in the modified form are not capable of rotation with the shaft 13, but are rigidly secured to the wall 15 of the pump casing and the cap 35 16' of the chamber 17. As shown the end portions 35 of the inner and outer seals overlap and are secured to flanges 15' and 16" of the plates 15" and 16' respectively, while the headers 36 of the seals slidably 40 engage the shaft 13 and have a bearing engagement with the oppositely disposed annular shoulders formed by the enlarged portion 24 of the shaft. For normally urging the headers 36 into bearing engagement with the said shoulders the coil springs 45 37 are provided, which as shown are housed within the expansible elements 38 and surround the shaft 13 upon opposite sides of the enlarged portion thereof. 50

Thus from the foregoing, it will be apparent that the herein described apparatus renders possible the production of a commercially satisfactory arrangement that is simple and compact in construction which 55 makes its manufacture economically efficient.

What I claim as my invention is:

1. In combination, a pump having a wall provided with a fluid passage and a shaft opening, and provided about said opening 60 with a laterally projecting tubular portion constituting a fluid chamber, said chamber being in open communication with said passage, a plate secured to the outer end of said chamber and having a shaft opening, a plate within said chamber and secured

to said pump wall, a shaft in the openings aforesaid and provided intermediate its ends with an enlargement, means for conducting a fluid to said chamber, and means for preventing such fluid from flowing longitudinally of the shaft through the opening in the first mentioned plate, including bellows surrounding the shaft between said enlargement and plates aforesaid. 70

2. In combination, a pump having a wall 75 provided with a fluid passage and a shaft opening, and provided about said opening with a laterally projecting tubular portion constituting a fluid chamber, said chamber being in open communication with said passage, a plate secured to the outer end of said chamber and having a shaft opening, a shaft in the openings aforesaid and provided intermediate its ends with an enlargement, means for conducting a fluid to said 80 chamber, and means for preventing such fluid from flowing longitudinally of the shaft through the shaft opening in said plate, including a longitudinally expansible tube surrounding and extending longitudinally of said shaft between the enlargement and the plate aforesaid. 85

3. In combination, a pump having a wall provided with a fluid passage and a shaft opening, and provided about said passage 90 and opening with a laterally projecting tubular portion constituting a fluid chamber, said chamber being in open communication with the passage aforesaid whereby fluid in the chamber is always free to pass through 95 the passage into the pump, a plate secured to the outer end of said chamber and having a shaft opening, a shaft in the openings aforesaid, means for conducting a fluid to said chamber at a point between the pump 100 wall and plate aforesaid, and tubular means extending longitudinally of said shaft between said pump wall and plate, preventing the escape of fluid along the shaft through 105 the plate but permitting the fluid to enter 110 the passage in the pump wall. 110

4. The combination with a pump casing wall provided with a fluid passage and a shaft opening, and provided about said passage opening with a laterally projecting tubular portion constituting a fluid chamber in open communication with the passage aforesaid, said chamber being provided at one side thereof with a fluid inlet, a plate secured to the outer end of said tubular portion and having a shaft opening therein, a shaft in the openings aforesaid, means for conducting a fluid to said inlet, and means associated with said shaft and plate for preventing the fluid from said inlet from 120 escaping along the shaft through the opening in said plate. 125

5. The combination with a pump casing wall provided with a fluid passage and a shaft opening, and provided about said pas- 130

sage opening with a laterally projecting tubular portion constituting a fluid chamber in open communication with the passage aforesaid, said chamber being provided at 5 one side thereof with a fluid inlet, a plate secured to the outer end of said tubular portion and having a shaft opening therein, a shaft in the openings aforesaid, means for conducting a fluid to said inlet, a plate 10 within said chamber and secured to said pump casing wall, and means preventing the fluid supplied to said chamber from the inlet from passing along the shaft within said chamber including sealing elements 15 associated with the shaft and first and second mentioned plates aforesaid.

In testimony whereof I affix my signature.
HAROLD A. GREENWALD.
